WALL CLIP

James W. Pearce, Philadelphia, Pa.; I. Russell Bush and Dorothy D. Pearce, administrators of said James W. Pearce, deceased, assignors to Arthur J. Purssell, Narberth, Pa.

Application February 29, 1932. Serial No. 595,683

4 Claims. (Cl. 72—115)

This invention relates to improvements in wall clips and it consists of the matters hereinafter described and more particularly pointed out in the appended claims.

5 One of the objects of the present invention is to provide a simple and efficient clip for use in connection with furring bars of a building wall, to support certain wall panel receiving devices in a position spaced from said bars.

10 A further object of the invention is to provide a clip of this kind which can be made from strip metal without waste and which is formed at one end with a laterally opening recess for operative engagement with an associated furring bar and which is provided at the other end with parts arranged for engagement with certain members of channel-like cross section in which marginal parts of panel-like wall elements are held to provide a part of the finished wall.

15 The above mentioned objects of the invention, as well as others, together with the many advantages thereof, will more fully appear as I proceed with my specification.

In the drawing:—

20 Fig. 1 is a vertical sectional view through a hollow wall in which clips embodying the preferred form of my invention are employed.

Fig. 2 is a horizontal sectional view through the same as taken on the line 2—2 of Fig. 1.

25 Fig. 3 is a detail perspective view on an enlarged scale and illustrates the manner of spacing the binder bars from the furring bars by means of my novel clip.

Fig. 4 is a plan view of a blank from which 30 the clip or bracket shown in Figs. 1, 2 and 3, is made.

In general, my improved clip comprises a strip of sheet metal having a laterally opening recess in one end adapted to practically surround a 35 furring bar with which the clip is used, a part of said clip adjacent said recess being formed to provide a tongue or finger which may be bent into attaching relation with a part of the furring bar and other parts of said clip adjacent said recess being formed to provide reinforcing flanges. The other end of said clip is formed to provide 40 longitudinally spaced right angle tongues or fingers for engagement with a wall panel receiving element which is held in the desired spaced relation with respect to said bar by said clip.

45 Referring now in detail to that embodiment of the invention, illustrated in the accompanying drawing:— 1 indicates a floor or the like, which provides a footing upon which a wall 2 is erected. Said wall in this instance includes a plurality of

perpendicularly disposed furring bars 3 aligned but spaced the desired distance apart in the plane of the wall. Each furring bar is secured to not only the floor 1 or footing in any suitable manner, but is also secured to certain ceiling parts (not shown) in any approved manner. Preferably, and as herein shown, each furring bar is in the form of a channel arranged with its web extending transversely of the wall.

50 Associated with each furring bar and vertically spaced thereon, is a plurality of clips or brackets 4 embodying my invention and one of which is best shown in Fig. 3. One end of each clip is formed for attachment with the associated furring bar, while the other end is adapted for operative engagement with certain horizontally disposed binder bars forming a part of the side of the finished wall, to hold said binder bars in laterally spaced relation with respect to the furring bars.

55 Said clip is made from a blank 5 of sheet metal of the desired length and thickness and which blank is shown in Fig. 4. Said strip is slit longitudinally at each end as at 6 and 7 respectively, along its median line, to there provide a pair of tongues or fingers 8, 9, 10 and 11 respectively. In one side of that end of the blank 5 associated with the tongues or fingers 10—11 is formed a transverse slit 12 and this slit while it terminates at its inner end in the plane of the slits 6 and 7, is spaced from the inner end of the slit 7, a distance equalling the width of the furring bar or channel with which it is to be used.

60 In forming the clip from the blank described, the finger 8 is bent downwardly at a right angle about a fold line 13 disposed in the plane of the inner end of the slit 6 while the finger 9 has its extremity bent down at a right angle to form a hook 14. The finger 11 and that part 11a of the blank between it and the slit 12 is bent downwardly at a right angle along a fold line 15 which is disposed in the plane of the slit 7 and then said finger 11 is bent forwardly about a transverse fold as a whole. Thereafter the finger 10 is bent downwardly at a right angle about a fold line 16. Thereafter the finger 10 is bent downwardly at a right angle about a fold line 17 which is coincident with the fold line 16.

65 After the blank has been folded as described, a clip or bracket is provided having a recess in its side at one end which will receive a furring bar 3 and which recess is of a depth approximating the depth of the flanges of said bar as best shown in Fig. 3. When the clip is applied to the bar, the back of the web of said bar is engaged with the part 11a of the clip after which the end of the finger 11 is bent to provide a hook 70

18 that clinches over the edge of the associated flange of the furring bar as best shown in said Fig. 3. When the clips have thus been engaged upon the furring bar, they stand at a right angle to the bar in the direction of the web of the same.

In building up a wall with the aid of my improved clip, I secure to the floor or footing 1 in a line parallel with but spaced from the furring bars the proper distance, an upwardly facing 10 channel-like edge binder bar including a base 19 and spaced flanges 20—20. A sheet of plaster or other wall board 21 is disposed with its bottom margin in said binder bar. I then take a reinforcing bar 22 which as best shown in Fig. 3, 15 includes a base 23 and reversely facing loops 24 along each side margin instead of one finger or loop facing in one direction only, and engage the finger 9 of a clip 4 upon the top of said base with the hook 14 engaging one edge thereof and with 20 the shoulder as formed by the finger 8 engaging the other edge of the base as best shown in Fig. 3. Thereafter the clip and the binder bar may be slid down the furring bar so that the loops 24 on 25 the reinforcing bar will receive the top margins of the wall board sheet 21.

Thereafter, another wall board sheet 21a is engaged with its bottom margin disposed upon the base 23 between the loops 24 on the top of the base 23 thereof and this will hold the fingers 9 of the clips 4 in place and then the top margin of said second sheet 21a is engaged in the next 30 binder bar 22 above. This operation is carried on until the desired height of the wall is reached and which, of course, terminates at the ceiling, 35 before mentioned.

Expanded metal, fabricated lath or other plaster supporting base 25 is then applied to the furring bars and is preferably bound in place by wires 26. If desired, plaster board may be 40 used as the plaster base for this side of the wall, in connection with binder bars 22 employed at the margins thereof for holding them in operative edge to edge engagement and which binder bars may be tied in any suitable manner to the furring 45 bars. Thereafter the plaster 27 is applied to said lath to form one side of the wall and then plaster 28 is applied to the exposed faces of the sheets 21—21a. This plaster encloses those loops 24 engaged with said faces of said sheets and said loops then act to reinforce the joints between them. Furthermore, such plaster also acts to 50 more securely tie the fingers 6 and 7 to the reinforcing bars.

From the above, it is apparent that I am able 55 to produce a wall including but about one-half the number of furring bars as necessary in walls of this kind, as heretofore made, because one side of the finished wall is hung upon said bars and the other side is held in spaced relation by 60 my improved spacing clips or brackets mentioned.

Such a structure is light in weight and is hollow not only for insulating purpose but also to conceal such wiring and conduits as are required and which may rest directly upon said clips or brackets. Such a wall may be quickly erected at a low cost and as it contains no combustible material, it is absolutely fireproof.

While in describing the invention, I have referred in detail to the form, arrangement and construction of the improved clip as well as the parts with which it is associated in erecting a building wall, the same is to be considered only as illustrative and I do not wish to be limited thereto except as may be specifically set forth in the appended claims.

I claim as my invention:—

1. A clip of the kind described, formed at one end with a recess in one side and there having a finger bendable over toward said recess and being split longitudinally at its other end to provide fingers, one of which is formed to provide a hook at its end and the other of which is bent at substantially a right angle to the clip to provide a shoulder spaced longitudinally from said hook.

2. A clip of the kind described comprising a body 100 having a recess in one end of one side thereof, said recess being defined along its back and one end by a flange disposed at a right angle to said body, the other end of said body being split longitudinally to provide fingers, one of which terminates in a hook and the other of which is bent to provide a shoulder spaced from and parallel with the hook.

3. A clip of the kind described comprising a substantially flat body having a recess in one end of one side thereof, a part of said recess being defined by a flange extending downwardly from the plane of the body and another part of said recess being defined by a flange extending laterally of said body toward one edge and of a length greater than the depth of said recess the other end of said body being split longitudinally to provide fingers, one of which extends in a plane at a right angle to the body and the other of which projects beyond the plane of the first mentioned one and terminates in a hook flange.

4. A clip of the kind described embodying therein a substantially flat body having a recess in one end of one side thereof, the inner part of said recess being defined by a downwardly bent flange and an end part of said recess being defined by a laterally bent flange, there being a third and downwardly bent flange at the recessed end of the body, all of said flanges being arranged at a right angle to the body and to each other, the other end of said body being split longitudinally to provide a downwardly bent finger and a second finger extending beyond the same and terminating in a downwardly bent hook flange.

JAMES W. PEARCE.
